UNITED STATES PATENT OFFICE

2,571,493

MOPHEAD CLAMPING STRUCTURE

Manuel Seemann, Cleveland, Ohio

Application June 24, 1949, Serial No. 101,134

3 Claims. (Cl. 15—153)

1

This invention relates to a novel clamping structure for detachably clamping mop material to a handle and which is particularly intended and adapted for holding mop yarns employed in the application of bitumen in the roofing and waterproofing trades and which is the most difficult type of yarn or mop material to clamp to a mop handle.

Another object of the invention is to provide a clamp structure by the use of which yarn or mop material may be applied to the clamp structure when the original mop material wears down to an extent making it impractical to use further and which may be accomplished without removing the original yarn or mop material.

Another object of the invention is to provide a mop head clamp having no sharp edges which will cut or wear the yarn adjacent the clamp structure.

Still a further object of the invention is to provide a clamp structure having an adjustable clamping head which is readily removable so that additional yarn may be added to a mop used for applying bitumen while the mop material is hot and which will afford ample room, with the adjustable clamp removed, for adding the new yarn without danger of the new yarn catching on the sticky coating of the old mop material and whereby the yarn may be much more effectively clamped than if applied while the mop is cold.

Still a further and particular important object of the present invention is to provide a clamp structure having a single readily detachable nut and bolt which can be quickly and easily replaced when the threads become worn or damaged by contact with the bitumen, which frequently occurs, at a small fraction of the cost of replacing the entire mop as is conventionally required.

Various other objects and advantages of the invention will hereinafter become more fully apparent from the following description of the drawing, illustrating a presently preferred embodiment thereof, and wherein:

Figure 1 is a side elevational view, partly in vertical section showing the novel clamp structure with yarn clamped therein and with a portion of a handle shown secured thereto;

Figure 2 is an edge elevational view of the same parts, taken at right-angles to Figure 1;

Figure 3 is a cross sectional view of the clamp structure, with the mop material omitted, taken substantially along a plane as indicated by the line 3—3 of Figure 1;

Figure 4 is a fragmentary longitudinal sectional

2

view of the clamp structure, taken substantially along a plane as indicated by the line 4—4 of Figure 3; and

Figure 5 is an exploded perspective view, partially fragmentary, of portions of the clamp structure.

Referring more specifically to the drawing, the novel mop head clamping structure constituting the invention is designated generally 6 in its 10 entirety and includes an elongated socket member 7 having an upwardly opening end adapted to receive an end 9 of an elongated mop handle and which is secured therein by one or more fastenings 10 which extend diametrically through 15 the socket 7 and handle end 9. The end of the handle 9 which is disposed in the socket 7 is spaced a considerable distance from the bottom wall 8 of said socket which is provided with an opening 11.

20 An elongated, substantially U-shaped bail or yoke 12 is secured to the socket 7 and projects longitudinally from its bottom end 8. The terminals of the substantially parallel legs 13 of the bail or yoke 12 straddle the socket 7, adjacent its bottom 8 and are secured thereto in any suitable manner as by welding as indicated at 25 14. The arcuate outer portion 15 of the bail 12 is spaced a substantial distance from the bottom 8 and forms a stationary clamping element or jaw.

20 A movable clamping element or jaw, designated generally 16, is slidably and removably mounted in the bail 12 for movement longitudinally thereof toward and away from the stationary jaw portion 15 and comprises an elongated plate 17, as best seen in Figures 3 and 5, having arcuate or substantially semicircular notches 18 in the ends thereof and which are adapted to slidably engage the adjacent portions of the bail legs 13. One side of the plate 17, constituting its upper side, 35 is provided with an elongated web 19 which may be formed integral therewith or suitably secured thereto. The web 19 extends longitudinally of the plate 17, between the notches 18 and is equally spaced from the two side edges of said plate. The web 19 is provided with an outwardly opening notch 20 intermediate of its ends.

An elongated feed screw 21 has a head 22 at one end thereof and which is preferably circular in cross section and a portion of which is adapted to be received in the web notch 20. The outer end of the head 22 is provided with an outwardly opening slot or kerf 23 which extends diametrically thereacross and which is adapted to receive the portion of the web 19 disposed beneath the notch 20 for non-rotatably connecting the screw

21 to the jaw 16 when the web 19 is in engagement with the kerf 23. The screw 21 carries a nut 24.

To assemble the screw 21, nut 24 and adjustable clamping jaw 16 on the remainder of the clamping structure 6, the nut 24 may be initially advanced on the screw 21 to a position adjacent the head 22 after which the threaded end of the screw is inserted into the socket 7 through its opening 11 which is sized to slidably receive the screw 21 and so as to position the screw head 22 adjacent the socket 7 and remote to the stationary clamping jaw 15 of the bail 12. Thereafter and preferably before the movable clamping jaw 16 is applied, the yarn or mop material 25 is inserted through the bail or yoke 12 and with the intermediate portion thereof disposed adjacent the outer end of said bail. With the screw 21 retracted so that its head 22 is disposed adjacent the notch 1, the movable clamping jaw 16 can be inserted into the bail 12 and then swung to a position transversely thereof and so that the notches 18 will slidably engage the inner halves of the bail legs 13, as seen in Figure 3 and will retain the plate 17 in a position with its plane at substantially a right angle to the longitudinal axis of the bail 12. The screw 21 can then be moved downwardly of the bail 12 for engaging its head 22 in the notch 20 and its kerf 23 with the web 19, as previously described and as best illustrated in Figures 1 and 4. The screw 21 will thus be held against rotation relatively to the socket 7 and bail 12 so that by turning the nut 24 in a direction to move it away from the head 23, said nut will exert a pressure against the socket bottom 8 for feeding the screw 21 outwardly thereof for advancing the jaw 16 toward the stationary jaw 15 for clamping the intermediate portion of the yarn 25 between said jaws 15 and 16. The yarn 25 is of the type for use in the roofing or waterproofing trade and in what is known as a "flashing mop," said yarn being applied in skeins and varying from two to five skeins ordinarily.

By backing off the nut 24 toward the screw head 22, the movable jaw 16 can be removed and additional yarn 25 applied when required, without removing the old yarn and after which the movable clamping jaw 16 can be replaced and advanced into a clamping position by the screw 21 and nut 24, as previously described. The pressure on the threads of the nut and screw 21 and the carbon and other substances of the bitumen to be applied with the mop will all tend to reduce the life of these threads so that the threads will quickly become too badly worn or damaged for further use. Whereas it has been conventional under such circumstances to replace the entire mop, it will be readily apparent that with the clamp structure 6 the screw 21 and nut 24 can be quickly and easily removed and replaced at a very small fraction of the cost of replacing the entire mop.

Various modifications and changes are contemplated and may obviously be resorted to, without departing from the spirit or scope of the invention as hereinafter defined by the appended claims.

I claim as my invention:

1. A mop head clamp comprising an elongated mop handle receiving socket having a bottom provided with an opening, an elongated substantially U-shaped bail having substantially parallel legs, the terminals of said legs straddling said socket adjacent its bottom and being secured thereto, said bail projecting from the bottom end of the socket and longitudinally thereof, the intermediate portion of said bail being spaced a substantial distance from the socket bottom and defining a stationary clamping jaw, a movable clamping jaw slidably and detachably mounted in said bail and comprising a plate having outwardly opening notches in the ends thereof slidably engaging the legs of the bail when said plate is disposed transversely therebetween, said movable jaw including a web projecting from one side of said plate and disposed perpendicular thereto, a feed screw loosely engaging the opening of said socket and having a head extending into the bail and provided with a kerf detachably engaging said web for detachably and non-rotatably connecting the feed screw and movable jaw, and a nut mounted on said feed screw for bearing engagement with the outer side of the socket bottom for advancing the feed screw outwardly of said socket when said nut is turned in a direction away from the screw head for displacing the movable clamping jaw toward the stationary clamping jaw, said bail being adapted to contain mop material disposed between the stationary and movable clamping jaws and clamped in the bail thereby.

2. A mop clamp as in claim 1, the distance between said bail legs being substantially less than the distance between the socket bottom and stationary clamping jaw.

3. A mop clamp as in claim 1, said web being disposed longitudinally of the plate and having a notch in its outer edge for detachably receiving the screw head.

MANUEL SEEMANN.
